UNITED STATES PATENT OFFICE

JOHN J. MAHLER, OF NEW YORK, N. Y., ASSIGNOR TO UNITED SHOE MACHINERY CORPORATION, OF PATERSON, NEW JERSEY, A CORPORATION OF NEW JERSEY

LAST

Application filed May 31, 1924. Serial No. 717,017.

This invention relates to lasts, particularly to lasts for use in the manufacture of stitchdown shoes, that is, shoes in which the outturned margin of the upper is secured to the projecting margin of the sole.

In the manufacture of the better grades of stitchdown shoes, a sole larger than the last bottom is secured to the bottom of the last and the upper is worked over the last under tension and tucked into the angle between the side of the last and the projecting margin of the sole, where it is permanently secured, usually by staples. In the case of a single-sole stitchdown shoe, the sole referred

to is the only one with which the shoe is provided, and to complete the shoe a welt is usually applied to the outturned flange of the upper and sewed with the upper to the sole.

This shoe is cheap to manufacture and very flexible but is not repairable except with shoe factory facilities. In the case of a two-sole stitchdown shoe, the first sole, to which the upper and lining, if any, are preliminarily fastened in outturned relation, may be comparatively thin, and a thicker sole is then applied and secured by a seam extending through the welt, upper, lining and the two soles. This shoe costs a little more in labor and material than the single-sole stitchdown and is not quite so flexible but has the decided advantage that it may be repaired with the usual repair shop facilities. The presence of the lining in the shoe edge, however, renders satisfactory edge finishing difficult.

A third and still better type of stitchdown shoe has three soles, the first or innersole corresponding in shape and size to the last bottom. The lining of the shoe is then lasted inwardly and secured, for example, by cement, to the innersole. A thin middle sole, which is larger than the last bottom, is then applied and the upper lasted and preliminarily fastened to the margin of the middle sole. An outsole and welt are then applied

and the welt, upper, innersole and outsole secured together by a strong seam. This shoe has exceptional strength and durability, the upper is well supported by the innersole, the edge may be readily finished, and the outsole may be easily replaced when worn out.

While the better grades of stitchdown shoes, particularly the three-sole stitchdown shoes of the type above referred to, have competed to a substantial extent with shoes of other types, stitchdown shoes as heretofore made, whether one, two or three-sole shoes, and of however good grade, have, generally speaking, been at a disadvantage in competition, particularly with corresponding grades of McKay sewed and welt shoes, principally because of their lack of stylish appearance. This handicap is especially conspicuous as to the better grades of stitchdown shoes, particularly stitchdown shoes of the three-sole type made in the larger sizes intended to be worn by adults, since, while such shoes have excellent wearing qualities and are of a grade intended to compete with McKay sewed and welt shoes, their lack of style and generally inferior appearance, in comparison with welt and McKay sewed shoes, very greatly limit stitchdown shoe production.

This lack of style and acceptable appearance in stitchdown shoes as heretofore manufactured is largely due to the fact that such shoes do not have the acute angle between the upper and sole projection characteristic of welt and McKay shoes and referred to generally as the "welt crease." This acute angle is formed by the drawing of the upper over the bottom of the insole and against the edge of the insole. Attempts have been made to secure this effect in stitchdown shoes by beveling the last bottom or by beveling the insole which covers the last bottom, or both, but with only partial success because of the difficulty of working the outturned upper into an angle necessarily so sharp. All lasts used for stitchdowns except for the bottom beveling, when used, have, however, been substantially like welt and McKay lasts, that is, they have had the largest periphery of the forepart of the last substantially at the bottom of the last.

Objects of this invention are to provide a last for stitchdown shoes by the use of which the welt crease characteristic of welt and McKay shoes may be produced, substantial economy in bottoming material effected,

and the proper positioning of the welt in the angle of the upper facilitated.

With these objects in view features of the invention consist in a stitchdown last having the greatest periphery of its forepart spaced above the plane of its bottom surface, the side of the last between the line of largest periphery and the smaller periphery of the last bottom being curved inwardly. As shown herein, this curve is a circular curve of constant radius from the ball line on the outer side of the last substantially to the tip line on the inner side of the last, and from the tip line on the inner side of the last to the ball line on that side the radius of the curve gradually increases, the line of largest periphery therefore gradually receding from the plane of the last bottom. Stated in another way, the projection of the last upon the plane of the last bottom is larger than the last bottom and extends beyond it at all points about the forepart, the projection extending a uniform distance beyond the last bottom from the ball line on the outer side of the last substantially to the tip line on the opposite side of the last and increasing from that point to the ball line on the inner side of the last.

The size of the insole required for a given last embodying this invention is therefore smaller than the insole required for a usual last of that size, and similar economies are effected in the other sole or soles required according to the type of stitchdown being manufactured.

Furthermore, when a shoe lasted on a last embodying this invention is presented to the table of the outsole sewing machine for the operation of sewing the welt, upper and sole together, the table engages that portion of the side of the last between its line of greatest periphery and the bottom of the last, and the welt guiding surface of the table can extend further inwardly of the shoe than it can when usual lasts are employed. The welt is thus crowded closely into the angle of the upper formed between the side of the last and the extending margin of the sole or, if the shoe has an insole, into the angle formed between the edge of the insole and the extended margin of the sole. This pronounced acute angle in the welt crease produced in lasting over this last is maintained and enhanced in the operation of laying the welt and sewing it to the upper and outsole, with the result that a stitchdown shoe of very acceptable appearance is produced and one capable of favorable comparison with the welt or McKay product of equal or greater cost.

In the drawings,

Fig. 1 is a view of the bottom of a last embodying the invention;

Fig. 2 is a transverse sectional view of the last on the line C—D of Fig. 1, looking toward the rear end of the last;

Fig. 3 is a cross-section of the last on the line E—F of Fig. 1;

Fig. 4 is a longitudinal section of the toe end of the last on the line G—H of Fig. 1;

Fig. 5 is a transverse section similar to that of Fig. 2 of a last of larger size;

Figs. 6, 7 and 8 are transverse sections of shoes and lasts showing respectively a one-, two- and three-sole stitchdown shoe made on a last embodying this invention;

Fig. 9 is a diagrammatic view showing how the surface of the last to which the upper is shaped is related to the last bottom; and

Fig. 10 is a sectional view of a shoe and last showing its relation to the table of an outsole sewing machine.

Fig. 1 represents the bottom of a last embodying the present invention. The outer line K of the figure indicates the greatest periphery of the last, or the projection of the last upon the plane of the last bottom. The inner line L is the periphery of the last bottom. At the forepart, with which this invention is particularly concerned, it will be seen that the line K is spaced outwardly from the line L at all points. The line A—B represents approximately the ball line of the last, and the line E—F the tip line. It will be apparent that the distance separating the lines K and L is substantially uniform from the point B at the end of the ball line on the outer side of the last to the end E of the tip line on the inner side of the last, and that from the point E on the inner side of the last the distance between the lines gradually increases to the point A at the inner end of the ball line.

From the periphery L of the last bottom the sides of the last curve upwardly and outwardly to the line K in an unbroken curve without reentrant portions. Referring to Fig. 3, which is a section on the tip line E—F, it will be seen that the sides of the last below the line of greatest periphery are curved inwardly on an arc K—L which is preferably circular with its center M in a line parallel to the last bottom and passing through the line K of greatest periphery. The radius M—K of the curve K—L is of such length that the angle between it and the radius M—L to the point where the arc cuts the line of the last bottom, will be approximately 43.5 degrees. Between the points E and A on the inner side of the last, that is, from the tip line to the ball line, the distance that the line of greatest periphery extends beyond the edge of the last bottom as well as the distance of that line from the plane of the last bottom gradually increases. As shown in Fig. 2, however, as the length of the arc L—K increases at the section C—D to L—K' the radius increases to K'—M', and as the arc increases to L'—K'' at the ball line A—B the radius increases to K''—M''. 130

That is, the angular value of the arc remains constant. This relation will be clearer from the diagram of Fig. 9, at the right of which is represented the condition obtaining 5 around the periphery of the last from the point B to E (Fig. 1). Here the line P K is equal to the distance the line of greatest periphery extends beyond the last bottom, and P L is equal to the heightwise spacing 10 of the line of greatest periphery above the plane of the last bottom. The line P L is the product of the sine of the angle K M L by the radius M L or R and M P is the product 15 of its cosine by the radius R. Referring to the angle K M L as m for convenience, $PL = R \sin m$, $MP = R \cos m$, and $PK = R (1 - \cos m)$. With the angle selected 20 for illustration (43.5 degrees) the ratio

$$\frac{\sin m}{1 - \cos m} = 2.5$$

that is, the heightwise displacement of the line of greatest periphery of the last from the plane of the last bottom is 2.5 times the 25 projection of that line beyond the edge of the last bottom. This relation holds for other parts of the periphery as represented at the left of Fig. 9, the dimensions increasing and the proportions remaining constant.

In Fig. 5 is represented a section of a last of larger size than that of Fig. 2. It will be seen that while other dimensions have been increased to provide increased capacity 30 for the shoe, the length of the arc K L remains the same as in the smaller size of Fig. 2. The arc L K' also is of the same length as the arc L K' of the smaller last. That is, in a set of lasts of all sizes, the length of the arcs at corresponding points will be the same. 35 It follows that a set of lasts each embodying this invention cannot be produced by pantographic reproduction of a given last as a model with all its dimensions proportionately increased or diminished, but that a set of lasts will be made having the characteristics defined and then each last of the set will be used as a model to produce other lasts of the same size.

40 Lasts previously employed for stitchdown work have been substantially like lasts for welt work, except that in some instances the margin of the last bottom has been beveled, and these lasts have had their line of greatest periphery, except for a short distance adjacent to the end of the ball line on the inner side of the shoe, substantially at the edge of the last bottom. It will be apparent therefore that a given size of last embodying this 45 invention has a bottom substantially smaller than a usual last of the same size. Thus, a substantial saving of sole leather is effected, not only for the innersole, when used, which corresponds in size to the bottom of the last, but also in the middle and outer

extension soles which may be correspondingly smaller without affecting the amount of extension of these soles beyond the edge of the innersole or beyond the last bottom.

Figs. 6, 7 and 8 illustrate respectively a one-sole, a two-sole and a three-sole stitchdown made over lasts embodying the invention. The surface of the last from the line K of greatest periphery over the top of the last to the corresponding line K' of greatest periphery on the opposite side of the last may be referred to as the upper shaping surface of the last, that is, the surface to which the upper will naturally conform without substantial lasting tension, and the surface from the line K or K' to the line L at the edge of the last bottom may be called the surface of the last to which the upper is shaped in lasting, since it requires the active operation of a lasting tool such as a stapling nozzle to conform the upper to this surface. In each instance, as shown, the upper 10 has been shaped to this inwardly curved surface and secured, for example by staples, to the sole. In Fig. 6 a single sole 12 is shown and the staples 14 are driven part way through the sole and are not clinched. In Fig. 7 an extension innersole 16 is shown through which the staples 17 are driven and clinched. In Fig. 8 an innersole 18 of the same size as the 50 bottom of the last is used, over which the lining 20 is lasted, as shown, and secured, for example by cement, the upper being lasted and secured by clinched staples 17 to an extension innersole or middle sole 19 and an outer sole 21 applied. In each case a welt 22 is applied to the outturned flange of the upper and secured by stitches 24 to the extension of the sole or soles employed.

Another advantage incident to the use of lasts embodying the invention is realized in the outsole sewing operation. The table 26 of the outsole sewing machine, shown in section in Fig. 10, engages the upper over the surface of the last to which the upper has been shaped, that is, between the lines K and L. The table has a ledge 28 which engages the edge of the welt 22 and forces it into the angle of the outturned upper. The inwardly curved contour of the last K L thus permits the inner edge of the welt 22 to be brought well inside the line K of greatest periphery of the last, with the result that the angle between the outer surface of the welt and the upper is sharp and well defined, that is, an acute angled welt crease is produced in stitchdown shoe work to a degree heretofore unattainable.

Having thus described my invention, what I claim as new and desire to secure by Letters 125 Patent of the United States is:

1. A last for use in the manufacture of stitchdown shoes having a forepart extending in a curved surface to the edge of the last bottom, the projection of the forepart upon 130

the plane of the last bottom extending beyond the last bottom by a uniform amount for the greater portion of the periphery of the forepart and increasing progressively for 5 the remainder of the periphery of the forepart.

2. A last for use in the manufacture of stitchdown shoes having a forepart the projection of which upon the plane of the last 10 bottom extends beyond the last bottom by an amount which is uniform from the ball line on the outer side of the last to the end of the tip line on the inner side of the last and increases from that point to the inner end 15 of the ball line.

3. A last for use in the manufacture of stitchdown shoes comprising an upper shaping surface and a bottom surface the periphery of which is less than that of the upper 20 shaping surface, the peripheries of said surfaces being connected by an unbroken curved surface having a substantially constant radius for the greater part of the distance about the forepart from ball line to 25 ball line.

4. A last for use in the manufacture of stitchdown shoes comprising an upper shaping surface and a bottom surface the periphery of which is less than that of the upper 30 shaping surface, the peripheries of said surfaces being connected by a curved surface of substantially constant radius from the end of the ball line on the outside of the shoe to the end of the tip line on the 35 opposite side of the shoe.

5. A last for use in the manufacture of stitchdown shoes comprising an upper shaping surface and a bottom surface the periphery of which is less than that of the upper 40 shaping surface, the peripheries of said surfaces being connected by a curved surface on a substantially constant radius from the ball line on the outer side of the last to the end of the tip line on the inner side of 45 the last and increasing in radius progressively from the end of the tip line to the end of the ball line on the inner side of the last.

6. A last for use in the manufacture of stitchdown shoes comprising an upper shaping surface and a bottom surface the periphery of which is less than that of the upper shaping surface, the peripheries of said surfaces being connected by a convexly 55 curved surface which for a portion of the periphery of the last gradually increases in radius in a direction rearwardly of the last.

7. A last for use in the manufacture of stitchdown shoes having the greatest periphery of its forepart projecting beyond the edge of the last bottom by a uniform amount for the greater portion of its periphery and spaced heightwise of the last from the plane 60 of the last bottom, said heightwise spacing being more than twice the amount which the 65

greatest periphery of the last extends beyond the edge of the last bottom.

8. A last for use in the manufacture of stitchdown shoes having its line of greatest periphery substantially spaced heightwise of 70 the last from the last bottom, the side of the last from said line of greatest periphery all the way to the edge of the last bottom being on a circular arc whose center is in a line parallel to the last bottom and passing 75 through the line of greatest periphery.

9. A last for use in the manufacture of stitchdown shoes having its line of greatest periphery substantially spaced heightwise of 80 the last from the last bottom, the side of the last from said line of greatest periphery to the edge of the last bottom being on an arc of approximately 43 degrees whose center lies substantially in a line parallel to the last bottom passing through the line of greatest periphery.

10. A last for use in the manufacture of stitchdown shoes having its line of greatest periphery substantially spaced heightwise of the last from the last bottom, the side of the 90 last from said line of greatest periphery all the way to the edge of the last bottom being on a circular arc, and said arc being such that one minus the cosine of the angle subtended by said arc is proportional to the amount the 95 line of greatest periphery extends beyond the edge of the last bottom and the sine of said angle is similarly proportional to the heightwise spacing of said line above the last bottom, the ratio 100

$$\frac{\text{sine}}{1-\text{cosine}}$$

being substantially 2.5.

11. A last for use in the manufacture of 105 stitchdown shoes having its line of greatest periphery substantially spaced heightwise of the last from the last bottom, the side of the last from said line of greatest periphery to the edge of the last bottom being on a circular arc whose center is in a line parallel to the last bottom and passing through the line of greatest periphery, the distance from the line of greatest periphery to the plane of the last bottom being everywhere substantially two and one-half times the distance which the line of greatest periphery extends beyond the last bottom.

In testimony whereof I have signed my 110 name to this specification.

JOHN J. MAHLER.
